COMPUTING DEVICE

Hazlehurst R. Noyes, Los Angeles, Calif.

Application June 10, 1946, Serial No. 675,524

9 Claims. (Cl. 235—78)

1

The present invention relates to a computing device, and more particularly to a device for computing and indicating game scores, as in the game of bridge.

In playing a game of bridge, each hand is scored individually and the scores run from a minimum of 20 on up to scores at times in excess of 1000 points on a single hand. The score is counted in units of tens, hundreds and thousands.

In the past it has been customary to keep track of the score on a paper pad, two scoring columns being provided, one column for each side or pair of players. These columns customarily are headed "We" for the side keeping the score and "They" for the opponents. Since some of the scored points do not count toward game, it is necessary when the game point score is less than game, to score the game points separately. Such game points are, however, included, with the other points scored, in the total score. Also, it is necessary to indicate when a side has won a game, in rubber play, and therefore is "vulnerable."

After playing a rubber or, at times, after a single game of bridge in case the play is not by rubbers, it is necessary to total the scores of both sides. The matter of keeping score and totaling the scores after each game or rubber is considered tedious by many bridge players and results in occasional errors through failure properly to add up the scores.

An object of the present invention is to make an improved and simplified game scoring device.

Another object is to make a device having a dial for dialing a plurality of numbers successively thereon, and having associated mechanism for totalling the numbers and displaying such total.

Another object is to make a game scoring device having separate scoring counters for each of a plurality of players or sides, each counter comprising a plurality of concentric and interacting discs arranged to total a plurality of successive scores counted thereon.

Another object is to make a game counter having a plurality of concentric, independently rotatable discs, one of said discs being arranged for manual rotation to tabulate a plurality of successive scores, the other discs being arranged for predetermined periodic operation by the manually rotatable disc, automatically to add the scores thus tabulated.

Another object is to make a game scoring device having a dialing disc and a plurality of scoring discs intermediate periodic connection for automatically totaling a score, the dial or discs being

arranged with their centers of gravity eccentric to their centers of pivotal mounting so that on a predetermined operation of the device the dials will return by gravity to an initial or "zero" position.

These and other objects of the invention will be more fully set forth in the following description and the accompanying drawings, of which there are five sheets. In the drawings:

Fig. 1 is a plan view of a scoring device embodying the present invention;

Fig. 2 is an edge elevational view of the device illustrated in Fig. 1 as viewed from the direction of the arrows 2—2 of Fig. 1;

Fig. 3 is an end elevational view of the device illustrated in Figs. 1 and 2;

Fig. 4 is an enlarged fragmentary sectional view of one half of the device taken on the line 4—4 of Fig. 1;

Fig. 5 is a similarly enlarged sectional view taken on the line 5—5 of Fig. 4;

Fig. 6 is an enlarged view in perspective of a pivot post employed in each of the scoring assemblies of the device;

Fig. 7 and Fig. 8 are plan and transverse sectional views, respectively, of an upper scoring disc;

Fig. 9 is an enlarged fragmentary sectional view taken on the line 9—9 of Fig. 7;

Figs. 10 and 11 are plan and transverse sectional views, respectively, of a non-rotatable disc;

Figs. 12, 13 and 14 are plan, bottom, and transverse sectional views, respectively, of an intermediate scoring disc;

Figs. 15 and 16 are plan and transverse sectional views, respectively, of a non-rotatable cam supporting disc;

Figs. 17 and 18 are plan and sectional views, respectively, of a dialing and outermost scoring disc;

Fig. 19 is a fragmentary plan view of a tension releasing lever used for zeroing the rotatable scoring discs;

Figs. 20 and 21 are plan and transverse sectional views, respectively, of a non-rotatable base disc; and

Fig. 22 is a plan view of a spring held needle for indicating partial game scores.

Referring to the drawings in detail, an oval base 10, which may be of plastic or wood, has a supporting member 11 (see Figs. 2 and 3) secured to the rear edge thereof to elevate the rear end of the oval base when placed on a horizontal surface, such as a table.

Two circular score computing assemblies 12

and 13 are mounted on the base 10. These score computers are operated by dialing the score on an outer rotatable disc 14. Since both of these scoring computers are similar to each other, one only thereof will be described.

Each of the score computing assemblies is mounted on a fixed base disc 15, shown in detail in Figs. 20 and 21. The base disc 15 has a beveled peripheral rim portion 17 and a planiform annular marginal face 18 located inwardly from the beveled edge portion 17. Nine numbers 16 from ten to ninety, by tens, are inscribed on the marginal face 18 of the base disc. The numeral 10 is located fifty-four degrees in a counter-clockwise direction of the three o'clock position on the face 18, and the other members are spaced successively at thirty-six degree intervals in a counterclockwise direction around this face. These numbers are arranged in this manner so as to be displayed through holes in the dialing disc 14, as shown in Fig. 1. A circular recess 19 is provided centrally of the upper face of the base disc 15 and a hole 20 is provided centrally through the base disc to receive a center post 21. An annular rim 22 surrounds the upper marginal edge of the center hole 20.

A cam 23 projects upwardly from the bottom of the central recess 19, as illustrated in Fig. 20. The purpose of this cam will be brought out later in the specification. Three supporting legs 24, 25 and 26 project downwardly from the lower face of the central portion of the base disc 15, each of these legs having an axial hole 27 therethrough. Bolts 28 (see Figs. 4 and 5) are inserted through the holes in these legs, and through registering holes provided in the oval base 10 to secure the base disc 15 to the oval supporting base 10.

A pair of bolts 29 and 30 (see Figs. 1, 4 and 5) are mounted in holes in the annular marginal portion 18 of the base disc 15. These bolts support a spring metal plate 31 by means of spacing sleeves 32 which surround each of the bolts 29 and 30 (see Fig. 4). The spring plate 31 has an elongated opening 33 therein through which are displayed numerical score totals which are added automatically by the operation of the computers 12 and 13, as will be described later herein. The plate 31 has a reduced neck portion 34, the notched upper side of which acts as a finger stop when dialing a score on the computer, as best shown in Fig. 1.

The central or inner end of the spring plate 31 has a hole therein to receive a screw 37 which is threaded into a threaded hole 38 in the enlarged upper end of the center post 21 (see Figs. 4, 5 and 6). The center post has a keyway 39 cut lengthwise therein, this keyway, as illustrated in Fig. 6, cutting into the threaded hole 38 in the center post. The spring plate 31 has a positioning stud 40 mounted eccentrically of the screw hole 35, the positioning stud 40 being adapted to enter a registering hole 41 (see Fig. 6) in the head of the center post 21 to hold the center post against rotation.

A friction reducing washer 42 is mounted between the enlarged head portion of the center post 21 and an upper scoring disc 43. This upper scoring disc, shown in detail in Figs. 7, 8 and 9, has a central opening 44 of a size to rotate freely on the center post 21. Ten equally spaced holes 45, located at equal distances radially from the central opening 44 are provided in the upper scoring disc 43. These holes 45 are each cut with a sloping side 47, as illustrated in the section of

Fig. 9, to assist an actuating ball to enter these holes for step-by-step advancement of the disc, as will be brought out later.

In addition to the ten holes 45, the upper scoring disc 43 has a hole 48 therein spaced radially outward beyond the holes 45. This outer hole 48 is adapted to receive a weight ball 49 which is of a size to rotate freely in the hole 48, the upper edge of the hole 48 being of reduced diameter to retain the ball 49 in the hole 48. A series of ten numerals 50 from zero to nine, by tens, are displayed around the margin of the upper scoring disc 43 to be visible from the upper side thereof. These numerals 50 are positioned between, and radially outwardly beyond, adjacent holes 45.

The numerals 50 preferably are made with their vertical axes normal to a radius of the disc intersecting them, and with their bases in a clockwise direction from such radius. This causes each of the figures 50 to read upright when in the three o'clock position on the dial indicated by the "zero" of the disc illustrated in Fig. 7. The weight hole 48 is offset ninety degrees in a clockwise direction from the "zero" numeral 50 on the upper scoring disc.

Beneath the upper scoring disc 43 an intermediate scoring disc 51 is mounted pivotally on the center post 21. The intermediate disc 51 is substantially thicker than the upper scoring disc 43, and has a top recess 52 of a size to receive the upper scoring disc 43 for free rotation therein. The depth of the top recess 52 is such that the top surface of the upper scoring disc 43 is flush with the top surface of the marginal portion of the intermediate scoring disc 51 surrounding the top recess 52 when friction reducing washers 53 and 54 are mounted on the center post, one above and one below a small non-rotative disc 55.

This arrangement is illustrated in Figs. 4 and 5. The intermediate scoring disc 51 has a smaller central depression 57 in the center of the top recess 52 therein. The small, non-rotative disc 55, illustrated in Figs. 10 and 11, is inserted in this depression 57, and is held against rotation relatively to the center post 21 by a tongue 58 which projects into the keyway 39 of the center post 21.

The intermediate scoring disc 51 has an annular groove 59 of substantially semi-circular cross section adjacent the marginal edge of the top recess 52. This groove 59 provides a runway for the weight ball 49. The weight ball 49 acts to return the upper scoring disc to zero position when released from frictional engagement with adjacent spacing washers by raising the center post 21 to release it from the pressure of the spring plate 31, as will be brought out later herein.

The underside of the intermediate scoring disc 51 has ten recesses 60 therein and also has a pair of zeroing weights 61 and 62 embedded in openings adjacent the periphery of the disc 51 which act to return the disc to zero position when it is released for free rotative movement. The intermediate scoring disc 51 also has an annular groove 63 in the under side thereof, this groove being located beneath the area in the top recess 52 between the annular semi-circular groove 59 and the marginal edge of the central depression 57. A hole 64 is provided through the intermediate scoring disc 51 within the area of the bottom groove 63. A ball 65 of a size to be freely rotatable in the opening 63 is inserted therein, and is spaced outwardly from the center post the

same distance as the ten holes 45 in the upper scoring disc 43.

Ten numerals 67 are provided on the marginal portion of the intermediate scoring disc 51, these numerals being in sequence from zero to nine. The numerals 67 are located in the spaces between adjacent recesses 60 in the bottom of the disc 51. The numerals 67 are positioned on the disc 51 in the same relative positions as those on the upper scoring disc 43, the zero being positioned substantially ninety degrees in a counterclockwise direction from a radius of the disc midway between the zeroing weights 61 and 62.

The lower scoring or dialing disc 14 has a central annular recess 69 in the upper surface thereof of a size to receive the intermediate scoring disc 51 for free rotative movement therein. The dialing disc 14 has a secondary annular depression 70 concentrically thereof in which a non-rotative disc 71, illustrated in Figs. 15 and 16, is mounted as illustrated in Figs. 4 and 5. The small disc 71 is held against rotation on the center post 21 by a tongue 72 which fits into the keyway 39 in the center post.

The small disc 71 has a center portion 73 of a thickness to support, with the addition of an intermediate friction reducing washer 74, the upper marginal surface of the intermediate scoring disc 51 on the same level as the marginal portion of the dialing disc 14. A marginal portion 75 of the small disc 71 is of reduced thickness, and has a cam 77 thereon to project upwardly therefrom. The cam 77 is located the same distance from the center of the disc 71 as the hole 64 for the ball 65 in the intermediate scoring disc 51.

The dialing disc 14 has a hole 78 therein, this hole being located the same distance from the center post as the ten recesses 60 in the intermediate scoring disc 51. This distance is also the same as that of the cam 23 on the non-rotatable base disc 15 from the center post (see Fig. 5). A ball 80 is mounted for free rotative movement in the hole 78. The dialing disc 14 has ten holes 81, which may be referred to as dialing holes, through the flat annular marginal portion 79 thereof. These holes are provided to permit manipulation of the dialing disc 14 by one's index finger in the same manner as the dial of an ordinary dial telephone.

A pair of zeroing weights 82 and 83, which may be of lead, are secured, as by means of plastic cement, to the undersurface of the marginal portion of the dialing disc 14. Ten numbers 84 from zero to ninety, by tens, are imprinted between the adjacent dialing holes 81 on the marginal portion 79 of the dialing disc 14, the zero being located ninety degrees in a counterclockwise direction from the dialing hole between the weights 82 and 83. Friction reducing washers 85 and 86 are mounted on the center post above and below the dialing disc 14, respectively.

A pressure release or zeroing lever 87, illustrated in detail in Fig. 19, has an elongated body portion 88 with a forwardly projecting central key or arm 89 formed integrally therewith. A pair of center post raising fingers 90 and 91 are formed to project angularly outwardly from the ends of the elongated body portion 88 in a direction oppositely to the central key portion 89. The elongated body portion 88 is bent at a slight acute angle on a longitudinal center line thereof, the apex of this bend comprising a fulcrum on which the lever is adapted to tilt. A pair of holes 92 and 93 are provided near the ends of the elongated body portion 88.

gated body portion 89, these holes being adapted to receive the legs 24 of the fixed base discs 15 nearest the upper or elevated rear side of the oval base 10.

The ends of the fingers 90 and 91 are positioned one beneath each of the center posts 21, so that by depressing the forward or key end 89 of the member 87, the fingers 90 and 91 press upwardly against the lower ends of the center posts 21. This raises the center posts against the tension of the spring plates 31, thereby leaving the rotatable scoring discs free to rotate to their zero positions under the action of their respective weights.

The ball 80 which may be of steel of the type used in ball bearings is mounted to rotate freely in the hole 78 in the dialing disc 14. As shown in Fig. 4, upon rotation of the dialing disc 14 this ball rolls around on the surface of the central recess 19 of the fixed base disc 15. The distance between the surface of the central recess 19 in the base disc 15 where the ball 80 rolls and the under side of the intermediate scoring disc 51 is slightly greater than the diameter of the ball 80. When the dialing disc 14 is rotated to where the ball 80 rolls up onto the cam 23, however, the ball is elevated thereby into one of the ten recesses 60 in the intermediate scoring disc 51. Further movement of the dialing disc 14 with the ball thus in engagement with the side of a hole in the intermediate scoring disc, causes the intermediate scoring disc to rotate with it. The length of the cam 23 is such as to cause the intermediate scoring disc to rotate one-tenth of a revolution, after which the ball 80 passes the cam and drops down onto the surface of the recess 19 where it is free to roll during another rotation of the dialing disc 14, as illustrated in Fig. 4, until the ball 80 again encounters the cam 23. In this manner the intermediate scoring disc is advanced one-tenth of a turn for each revolution of the dialing disc 14.

It will be noted in Figs. 4 and 5 that each of the rotatable scoring discs, 43, 51 and 68, is mounted between two non-rotatable members. These non-rotatable members, from the top down, comprise the head of the center post 21, fixed discs 55 and 71 and the base disc 15. Frictional engagement between the rotatable discs and the non-rotatable members is transmitted through the friction reducing spacing washers 42, 53, 54, 74, 85 and 86 and is controlled by the spring pressure of the plate 31 on the center post 21.

The ball 65 functions to turn the upper scoring disc 43 in the same general manner as the ball 80 in turning the intermediate scoring disc 51. The distance between the upper surface of the rim 75 of the fixed disc 71, and the base of the groove 63 in the lower face of the intermediate scoring disc 51 is slightly greater than the diameter of the ball 65. Thus the ball 65, carried for free rotation in the hole 64 in the intermediate scoring disc 51, rolls around on the rim 75 of the disc 71 until it encounters the cam 77. The cam 77 raises the ball 65 into engagement with one of the ten holes 45 in the upper scoring disc 43, thereby causing the upper scoring disc to turn with the intermediate scoring disc. The cam 77 is of a length to cause one-tenth of a complete rotation of the upper scoring disc 43 before the ball passes the cam and drops down onto the rim 75 of the fixed disc 71, thereby freeing the upper scoring disc from driven engagement with the intermediate scoring disc.

Each of the scoring assemblies 12 and 13 is pro-

vided with a part score marker which is used to indicate when a part score, or in other words, a score less than game score, is attained by either side. This part score marker also is employed to indicate when a side has won one game toward a rubber and therefore is "vulnerable."

The part score markers comprise pointers 94 of spring material such as bronze or light spring steel with a central opening adapted to pivot on the center post 21. The pointers 94 are retained on the pivot posts 21 by the arms 90 and 91 of the pressure release lever 87. The outer end of each spring pointer 94 is pointed as at 95 and is bent upwardly and inwardly to overlie the beveled outer edge 17 of its associated base disc 15. These pointers are free to swing through an arc of approximately one hundred and eighty degrees, at which point the legs 24 and 26 of the base disc arrest further pivotal movement of the pointer. The beveled edge portion 17 of the base disc 15 along this arc of movement of each of the pointers is divided into two substantially equal quadrants, and each quadrant in turn is divided into ten equal divisions numbered from 0 to 100 by tens, the game score in bridge being 100. These pointers are moved manually by the scorer to indicate part game scores. The first game of each side in a rubber is scored in the upper quadrant, and the second game in the lower quadrant. The pointers are not operatively associated with the automatic score totaling mechanism provided by the rotatable scoring discs.

The operation of the device is as follows. In starting a bridge game, assuming that the various rotatable discs are not in a zero position, the scorer presses down on the key portion 89 of the zeroing member 87. The zeroing member fulcrums on the angular bend in the body portion thereof and the arms 90 and 91 are raised thereby, lifting the center posts 21 against the tension of the spring plates 31. This frees the rotatable scoring discs from compressive engagement with the friction reducing washers interposed between the rotatable discs and the various non-rotatable elements of the device as above set forth.

When thus released, the weights associated with each disc tends to rotate it so that the weighted portion thereof will be at the lowest point with respect to the center post 21. If the weights do not fully restore all of the discs to their zero position, and this may occur when the device is new and the rotative bearing surfaces are not yet worn completely smooth, the entire device may be tilted so that the base 10 is vertical, which insures that all of the discs will return to their zero position. After the scorer has been in use for a while the bearing surfaces become smooth and the rotatable discs readily return to their zero positions upon release of the spring pressure on the center posts.

With the scoring discs thus zeroed, the part game score pointers 94 are moved to their uppermost zero positions, and the play begins. After the play of each hand the entire score made is dialed on the dialing disc of the side or sides making the score and part game scores are indicated by the pointers 94.

To give an example of the use of the scoring device, we will assume that, as the first hand of a rubber, the scorer's side bid and made, for example, three hearts, with one over trick. The game score would be 90 and the over trick would be 30.

The scoring assembly marked "We" is dialed by the scorer, first by placing his finger in the

dialing hole 81 through which the number "90" on the base disc 15 is visible, and rotating the dialing disc in a clockwise direction until his finger strikes the reduced neck portion of the spring plate 31. This brings the score marking numeral "90" on the dialing disc into the opening 33 in the spring plate 31. This rotation of the dialing disc 14 through nine-tenths of a revolution in a clockwise direction brings the ball 80 adjacent the ramp 23.

The scorer then places his finger in the hole 81 on the dialing disc through which the numeral "30" on the base disc 15 is visible and again rotates the dialing disc in a clockwise direction until his finger is stopped by the plate 31. As the dialing disc is rotated through the final ten degrees of its first complete rotation, the ball 80 is raised by the ramp 23 into one of the ten recesses 60 in the bottom of the intermediate scoring disc 31. As the dialing disc 15 is rotated further it carries the intermediate dialing disc through one-tenth of a rotation to bring the numeral "1" thereon within the opening 33 in the plate 31. The dialing disc 14 now has made one and two-tenths complete rotations so that the numeral "20" will be displayed on the dialing disc and the numeral "1" on the intermediate disc. Thus, the correct score of "120" is displayed through the opening in the plate 31.

The pointer 63 then is moved to indicate "90" on the first game score in its upper quadrant. Successive scores are tabulated in a similar manner. After a side has won its first game of a rubber, it marks its second game score in the lower quadrant of the game score divisions marked on the beveled sides 17 of its base disc.

When the score of one side reaches "990" both the ball 80 and the ball 65 will be adjacent their respective ramps 23 and 71. A further one-tenth revolution of the dial 14 therefore will advance the dialing disc to display the numerals "00," the intermediate disc "0," and at the same time will advance the upper scoring disc to display the numeral "1," thereby displaying the score of "1000." Thus the score of each side continues to be added automatically merely by dialing the scores of each side as they are made.

The use of the two-game scoring arrangement on the beveled marginal portion 17 of the base disc 15 shows at a glance whether or not a side is vulnerable and their part game score.

While I have illustrated a preferred embodiment of my invention, it will be apparent to those familiar with the art that various modifications may be made without departing from the spirit of my invention. It is desired, therefore, not to limit the invention except as specifically defined in the following claims.

I claim:

60. 1. A game score computer and indicator comprising a series of relatively superposed rotatable scoring discs each having score indicia thereon, non-rotatable members interposed between selected discs of said series, a cam on at least one 65 of said non-rotatable members and a ball caged in one of said rotatable members for free rolling movement in the path of said cam, said ball being vertically movable by said cam relatively to the disc in which it is caged, a rotatable disc above said ball having ten openings each adapted to receive said ball for clutch engagement between the disc having the openings and the disc caging said ball, said cam being shaped to elevate said ball to maintain such clutch engagement for one-tenth of a complete rotation of both of said discs,

2. A game score computer and indicator comprising a series of relatively superposed rotatable scoring discs, non-rotatable members interposed between selected discs of said series, a plate mounted to overlie said discs, said plate having an opening therein through which selected scores on said discs are visible, a cam on at least one of said non-rotatable members, a ball caged in one of said rotatable members for free rolling movement in the path of said cam, said ball being vertically movable relatively to the disc in which is caged the rotatable disc above said ball having ten openings adapted to receive said ball for clutch engagement between the disc having the openings and the disc caging said ball, said cam being of a length to maintain such clutch engagement for one-tenth of a complete rotation of both of said discs, thereby to advance the score indicia on both of said discs relatively to the opening in said plate.

3. A game score computer and indicator comprising a series of discs superposed in successively decreasing diameters, each disc bearing score indicia visible from above said disc, non-rotatable members interposed between selected discs of said series, a cam on at least one of said non-rotatable members, a ball caged in one of said rotatable members for free rolling movement in the path of said cam, said ball being vertically movable relatively to the disc in which it is caged, the rotatable disc above said ball having ten openings adapted to receive said ball for clutch engagement between the disc having the openings and the disc caging said ball, said cam being of a length to maintain such clutch engagement for one-tenth of a complete rotation of both of said discs, and a spring pressure plate mounted normally to urge said discs and said interposed non-rotatable members into relative frictional engagement with each other, said plate having an opening therein through which is visible selected score indicia on said discs.

4. A game score computer and indicator comprising a series of discs superposed in successively decreasing diameters, each disc bearing score indicia visible from above said disc, non-rotatable members interposed between selected discs of said series, a cam beneath one of said discs, and spaced inwardly from the periphery thereof, a ball caged in said one disc for free rolling movement in the path of said cam, said ball being vertically movable relatively to the disc in which it is caged, and normally depending below said disc, a rotatable disc above said ball having recesses in a multiple of ten adapted to receive said ball for clutch engagement between the disc having the openings and the disc caging said ball, said cam being of a height to raise said ball into clutch engagement with one of said recesses, and said cam being of a length to maintain such clutch engagement between said discs for a radial distance equal to the center to center distance of adjacent said recesses.

5. A game score computer and indicator comprising a series of discs superposed in successively decreasing diameters, each disc bearing score indicia visible from above said disc, non-rotatable members positioned below and interposed between the discs of said series, a cam on each of said non-rotatable members except the uppermost one, a ball caged in each of said rotatable members except the uppermost one for free rolling movement in the path of the cam on the non-rotatable member next below it, said ball being vertically movable relatively to the disc in

which it is caged, the rotatable disc above said ball having a multiple of ten openings in its lower face adapted to receive said ball for clutch engagement between the disc having the openings

5 and the disc caging said ball, said cam being of a height to raise said ball into one of said recesses, and being of a length to maintain such clutch engagement for a radial distance equal to the center to center distance between adjacent said recesses.

6. A game score computer and indicator comprising a base disc having a plurality of fixed numerical indicia arranged marginally thereof, a series of successive concentric rotatable scoring discs, superposed in successively decreasing diameters, the lowermost of said rotatable discs overlying the numerical indicia on the base disc and having a finger dialing opening over each numerical indicia on the base disc to display it there-

15 through, similar game score indicia on each of said rotatable discs, non-rotatable means en-

gaging each of said scoring discs normally re-
straining its rotation, a stationary cam mounted beneath each rotatable disc, except the uppermost
25 one, normally unactuated cam operated motion transmitting means carried in each rotatable disc except the uppermost one, said cam operated means being positioned to be engaged and moved vertically by a cam on each complete rotation of

30 the disc in which said motion transmitting means is carried, thereby to advance a disc beyond said disc from said cam a predetermined distance thereby to produce a predetermined change in the relative positions of the game score indicia
35 carried by said discs.

7. A game scoring computer and indicator comprising a stationary member having circum-
ferentially arranged score indicia thereon and presenting on its top surface a circumferentially
40 disposed cam, a dialing disc rotatably superposed on the stationary member and having an open-
ing therethrough, an upper scoring disc carry-
ing circumferentially arranged score indicia ro-
tatably superposed on the dialing disc concen-
trically therewith, and having a recess therein;
45 said cam, said opening and said recess being positioned to be brought into register upon ro-
tation of the dialing disc relative to the stationary member, and a motion transmitting member
50 loosely mounted in said opening; said motion transmitting member being movable by the cam, in response to predetermined rotation in one direction of the dialing disc, into engagement with the recess whereby, upon further rotation
55 of the dialing disc in said direction, to cause the scoring disc to rotate with the dialing disc.

8. A game scoring computer and indicator comprising a stationary member having circum-
ferentially arranged score indicia thereon and presenting on its top surface a circumferentially
60 disposed cam, a dialing disc rotatably superposed on the stationary member and having an open-
ing therethrough, an upper scoring disc carry-
ing circumferentially arranged score indicia ro-
tatably superposed on the dialing disc concen-
trically therewith, and having a recess therein;
65 said cam, said opening and said recess being positioned to be brought into register upon ro-
tation of the dialing disc relative to the stationary member, a motion transmitting ball loosely mounted in said opening; said motion transmit-
ting ball being movable by the cam, in response to predetermined rotation in one direction of the dialing disc, into engagement with the recess
70 whereby, upon further rotation of the dialing

11

disc in said direction, to cause the scoring disc to rotate with the dialing disc, and means providing radially aligned windows overlying said stationary member and said discs through which windows aligned score indicia on said stationary member and said discs may be viewed.

9. A game scoring computer and indicator comprising a stationary member having circumferentially arranged score indicia thereon and presenting on its top surface a circumferentially disposed cam, a dialing disc rotatably superposed on the stationary member and having an opening therethrough, an upper scoring disc carrying circumferentially arranged score indicia rotatably superposed on the dialing disc concentrically therewith, and having a recess therein; said cam, said opening and said recess being positioned to be brought into register upon rotation of the dialing disc relative to the stationary member, and a motion transmitting member loosely mounted in said opening; said motion transmitting member being movable by the cam, in response to predetermined rotation in one direction of the dialing disc, into engagement with the recess whereby, upon further rotation of the dialing disc in said direction, to cause the scoring disc to rotate with the dialing disc; the center of gravity of each of said discs being eccentric to

5

12

its axis whereby to impart gravity rotative movement to said discs, and yieldable means normally resisting rotative movement of the discs.

HAZLEHURST R. NOYES.
